Corporation, a corporation of Indiana

Application January 4, 1945, Serial No. 571,265

8 Claims. (Cl. 250—150)

1

This invention relates generally to space discharge devices and particularly to a novel deflection system for a primary electron beam utilized in connection with an electron multiplier for amplifying signals.

In a conventional electron multiplier primary electrons obtained in any suitable manner are multiplied by means of secondary electron emission. For amplifying signals it has been suggested to control the number of primary electrons entering the multiplier by means of a grid. In another prior electron multiplier utilized as an amplifier an electron beam is deflected by the signal to be amplified. The deflected beam is then directed through an aperture into the multiplier where the primary electrons are multiplied. Thus, the number of electrons entering the aperture is made dependent upon the deflection of the beam. This method has considerable merit for amplifying modulated carrier signals of the type obtained with a receiving antenna. It is particularly useful when it is desired to obtain cut-off of the electron beam with such a signal. However, considerable difficulties have been experienced heretofore with the amplification of weak signals of the order of magnitude of millivolts. In this case the angle of deflection of the primary electron beam is very small. In order to increase the angle of deflection of the primary beam it has been proposed to utilize comparatively long electrostatic deflection plates so that the electron beam is under the influence of the variable field for an extended length. However, this arrangement is not feasible when the transit time of the electrons is comparable to the rate of change of the electric field or, in other words, for high and ultra-high frequencies. The actual deflection obtained with a small angle of deflection of the beam may also be increased by using a very long tube. However, there are obvious physical limitations to this scheme.

It has also been proposed to use an electron multiplier with a target electrode having different secondary electron emitting properties at different parts of its surface. This target has been used in connection with a primary electron beam to obtain a variable output in dependence upon the deflection of the primary beam. However, this prior method is not sensitive enough for amplifying weak signals.

It is an object of the present invention, therefore, to provide a space discharge device for amplifying weak signals.

A further object of the invention is to provide cumulative deflection of a primary electron beam

2

in accordance with a signal and to multiply the secondary electrons liberated by the primary beam in an electron multiplier.

Another object of the invention is to provide a selective multiplication of a cumulatively deflected electron beam to effect amplification of a weak radio frequency signal.

In accordance with the present invention there is provided a space discharge device including 10 means for developing an electron beam. This electron beam is deflected in accordance with a signal. A secondary electron emissive element having a curved surface is interposed into the path of the electron beam. The secondary electrons liberated by the beam from the curved surface of the element emanating from predetermined directions are collected. As the number of secondary electrons is largest in a direction normal to the secondary emissive surface of 15 the element, the result is effectively a cumulative deflection of the beam. Preferably, an electron multiplier is used for multiplying the secondary electrons liberated from the curved surface of the element.

20 Alternatively, the multiplier used for amplifying the cumulatively deflected electron beam includes a first stage having a secondary emissive surface arranged so that the number of secondary electrons liberated therefrom varies in accordance with the deflection of the beam.

25 For a better understanding of the invention, together with other and further objects thereof, reference is made to the following description, taken in connection with the accompanying drawing, and its scope will be pointed out in the appended claims.

In the accompanying drawing:

Fig. 1 is a schematic representation of a space discharge tube embodying the present invention; 40 and Figure 1a is a plan view of an electrode utilized in the space discharge tube illustrated in Figure 1;

Fig. 2 is a schematic representation of another discharge tube where the secondary electrons liberated by a deflected electron beam are selectively multiplied in an electron multiplier; and

Fig. 3 is a plan view of an alternative construction of the first stage of the multiplier illustrated in Fig. 2.

Referring now more particularly to Fig. 1 of the drawing, there is provided a space discharge device including an evacuated envelope 1. Electron gun 2 is arranged in envelope 1 for developing and focusing an electron beam indicated at 3,

Electron gun 2 includes cathode 4, grid 5, first anode 6 and focusing cylinder 7 which are all connected to potentiometer 8 connected, in turn, to battery 10 having its positive pole grounded as shown.

Electron beam 3 is directed toward electrode 11 having a convex surface arranged opposite electron gun 2. The convex surface of electrode 11 is made secondary electron emissive in any suitable manner well known to those skilled in the art. Deflecting plates 12, 12, arranged to deflect electron beam 3, are interposed between focusing cylinder 7 and electrode 11 having a convex surface.

Deflecting plates 12 are connected to dipole antenna 13 arranged for intercepting modulated carrier wave signals. As will be explained hereinafter, the discharge device of the invention is particularly suited for amplifying weak signals of radio and high frequencies, that is, signals having a strength of the order of magnitude of millivolts. Antenna 13 is connected to deflecting plates 12 by leads 14, 14. Shunt coil 16 shunts leads 14. The mid point of shunt coil 16 is connected by lead 17 to focusing cylinder 7 and, hence, deflecting plates 12 have an average potential equal to that of focusing cylinder 7. Blocking condensers 18, 18 are interposed in leads 14 between shunt coil 16 and dipole antenna 13 to block the direct current potential from dipole antenna 13.

By means of potentiometer 8 cathode 4 may, for instance, be kept at a potential of about 1500 volts negative against ground. Control grid 5 should have a potential that is a few volts more negative than that of cathode 4. First anode 6 may have a potential which is about 300 volts positive against cathode 4. Lead 19 connecting electrode 11 to anode 6 keeps electrode 11 at the same potential as anode 6. Focusing cylinder 7 and deflecting plates 12 may be kept at a potential of about 400 volts negative against ground.

Any signals intercepted by dipole antenna 13 will create electric potentials of opposite polarity on deflecting plates 12, 12 and, accordingly, electron beam 3 is deflected in the thus created electric field. Secondary electrons liberated by electron beam 3 on the convex surface of electrode 11 pass through aperture 20 in shield 21, shown in plan view in Figure 1a. Shield 21 is kept by lead 24 at the same potential as first stage 22 of electron multiplier 23. Electron multiplier 23 comprises further multiplier stages 25, 26, 27 and 28 and a collector electrode 30. Multiplier stages 22, 25, 26, 27 and 28 are connected to potentiometer 8 so that each stage is kept at a potential that is about 200 volts more positive than that of the preceding stage. Thus, stage 22 and shield 21 may be kept at a potential of about 1000 volts negative against ground, while the last stage 28 may be kept about 200 volts negative against ground. Collector electrode 30 is connected to lead 31 connected, in turn, to load resistor 32. Lead 31 is at ground potential as shown. The amplified signal output may be obtained from output lead 33 across load resistor 32.

Referring now to the operation of the discharge device illustrated in Fig. 1, electron beam 3 is developed and focused by electron gun 2 and directed toward electrode 11 having a curved surface. Electron beam 3 is deflected in accordance with the signals intercepted by dipole antenna 13. It is to be understood, however, that the deflection of electron beam 3 in accordance with a signal may be effected in any other suitable man-

ner, the connection of deflecting plates 12 to dipole antenna 13 being shown for purposes of illustration only.

The primary electron beam impinging upon electrode 11 having a curved surface liberates secondary electrons therefrom. We may assume that only a very small portion of the secondary electrons liberated from the surface of electrode 11 follows the optical laws of reflection, that is, the angle of incidence equals the angle of deflection. The great majority of the secondary electrons, however, will be distributed following a cosine law with the maximum number of electrons at the normal of the reflecting surface. Hence, we may assume that most of the energy of the secondary electrons liberated from the surface of electrode 11 has an angular distribution which depends upon the radius of curvature of the surface of electrode 11 and the point where the primary beam impinges upon the surface of electrode 11. Thus, by suitably choosing the radius of curvature of the surface of electrode 11 even a small angular deflection of primary electron beam 3 will be sufficient to cause a considerable change in the angular distribution of the secondary electrons liberated thereby. It will be appreciated that the surface of electrode 11 could also be made concave instead of convex. In this manner a cumulative deflection of the electrons is obtained. In other words, the electrons of the primary beam are first deflected by deflection plates 12 in accordance with the signal to be amplified. Then secondary electrons liberated by beam 3 from electrode 11 are again deflected in accordance with the radius of curvature of the surface of electrode 11, and thus a cumulative deflection is obtained.

The number of secondary electrons passing through aperture 20 in shield 21 thus depends upon the cumulative deflection of primary electron beam 3. The secondary electrons passing through aperture 20 impact first electron multiplier stage 22 where they liberate, in turn, more secondary electrons. The stream of secondary electrons impacts successive multiplier stages, each time increasing the number of electrons liberated. The output current is collected by collector electrode 30, and an amplified output signal is developed across resistor 32.

If desired, electrode 11 having a curved surface may be so arranged with respect to primary electron beam 3 and aperture 20 that substantially no secondary electrons pass through aperture 20 when the beam is in its normal or undeflected position. The secondary electrons are then collected by shield 21 or by deflecting plates 12. In this case the discharge device of the invention acts substantially as a detector or more correctly as a half-wave rectifier.

It is also feasible to arrange collector electrode 30 behind aperture 20 and to omit the electron multiplier stages 22 and 25 to 28. The output signal may then be further amplified in a conventional manner.

Referring now to Fig. 2, in which like components are designated by the same reference numerals as were used in Fig. 1, electron discharge device 35 comprises electron gun 2. Electron gun 2 includes cathode 4, control grid 5, anode 6 and focusing cylinder 7 which may be connected to a source of potential in the same manner as illustrated in Fig. 1. Deflecting plates 12, 12 are connected through leads 14, 14 to a source of signals to be amplified. In the manner explained in connection with Fig. 1, electron beam 3

is focused and directed toward electrode 11 having a curved secondary electron emitting surface where it liberates secondary electrons. As explained hereinabove, the secondary electrons liberated from the surface of electrode 11 have their main energy in a direction normal to the surface of electrode 11. Therefore, when the radius of curvature of the surface of electrode 11 is sufficiently small, a small angle of deflection of beam 3 will produce a considerable change in the direction of the main energy of the secondary electrons liberated from electrode 11.

These electrons now fall upon the secondary emissive surface of electrode 36 forming the first stage of electron multiplier 37. Electron multiplier 37 includes the further stages 40, 41 and 42 which may be of the well known box type as illustrated. Each of stages 36, 40, 41 and 42 is kept at a suitable potential that is positive with respect to that of the preceding stage to attract the secondary electrons liberated therefrom. The electrons liberated from the last electron multiplier stage 42 are collected by collector electrode 43, and an output signal may be obtained from output lead 44.

The first multiplier stage 36 is arranged in such a manner that its secondary electron emissive properties vary along its surface. Shaded area 45 diagrammatically indicates that the secondary electron emissive properties of stage 36 increase in the direction towards the second stage 40. Such a surface can be prepared in a number of different ways. To this end the caesium or caesium oxide layer which is usually used for that purpose may be gradually increased in thickness toward that portion where the secondary emission factor should be highest.

It is also feasible to prepare the secondary emissive surface of stage 36 as illustrated diagrammatically in Fig. 3. Shaded area 46 indicates a secondary emissive material such as caesium or rubidium or oxides thereof. Area 47 is made of a material which has a secondary electron emission factor of unity or less, such as carbon black. Area 46 is wedge-shaped as shown. Circle 48 indicates diagrammatically the approximate area covered by the secondary electrons liberated from the surface of electrode 11 and attracted by multiplier stage 36. It is of course to be understood that a secondary electron beam does not have a well defined outline. When beam 48 moves from the right to the left in Fig. 3 it will be seen that it covers an increasingly wider portion of secondary emissive area 46 and, hence, the number of secondary electrons liberated thereby is increased correspondingly.

The electron discharge device of Fig. 2 operates in substantially the same manner as the one shown in Fig. 1. In accordance with the signal to be amplified, electron beam 3 is deflected across electrode 11. Depending upon the direction of incidence of beam 3, the angle of the main energy of the secondary electrons changes. These secondary electrons impinge upon first multiplier stage 36, where they liberate in turn further secondary electrons. The number of electrons liberated from multiplier stage 36 depends upon which portion of stage 36 the secondary electrons impinge, that is, upon the direction of incidence of the secondary electrons. In this way the output obtained from collector electrode 43 is made dependent upon the variation of the signal to be amplified. No aperture is required for the discharge device of the invention illustrated in Fig.

2. In this case multiplier stage 36 provides a selective multiplication of the electrons impinging thereon in dependence upon their direction of incidence.

If desired, the surface of electrode 11 may be arranged in such a manner with respect to electron beam 3 and first multiplier stage 36 that substantially no secondary electrons are liberated from multiplier stage 36 when beam 3 is undeflected. Thus, the discharge device of the invention may be used as a detector or rather a half-wave rectifier.

Although a box type electron multiplier has been shown in Fig. 2, it is to be understood that any type of multiplier having any desired number of stages may be used in connection with the discharge device of the invention.

While there has been described what are at present considered the preferred embodiments of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A space discharge device including means for developing an electron beam, means for deflecting said electron beam in accordance with a signal to be amplified, an element having a secondary electron emissive convex surface interposed into the path of said electron beam to obtain a cumulative deflection of the said beam, means for collecting secondary electrons liberated by said beam from said surface, and means interposed between said surface and said collecting means for selecting a number of secondary electrons varying in accordance with the deflection of said beam and with the angular distribution of said secondary electrons.

2. A space discharge device including means for developing an electron beam of substantially constant intensity, means for deflecting said electron beam in accordance with a signal to be amplified, an element having a secondary electron emissive curved surface interposed into the path of said electron beam to obtain a cumulative deflection of said beam, an electron multiplier mounted adjacent said secondary emissive curved surface to receive secondary electrons liberated by said beam from said surface, and means interposed between said surface and said multiplier for selecting a number of secondary electrons varying in accordance with the deflection of said beam and with the angular distribution of said secondary electrons.

3. A space discharge device including means for developing an electron beam, means for deflecting said electron beam in accordance with a signal, an element having a secondary electron emissive curved surface interposed into the path of said electron beam to obtain a comparatively large deflection of said beam with a comparatively weak signal, means for collecting secondary electrons liberated by said beam from said surface, and a shield having an aperture interposed between said surface and said collecting means.

4. A space discharge device including means for developing an electron beam, means for initially deflecting said electron beam in accordance with a received signal, an element having a secondary electron emissive curved surface disposed in the path of said electron beam for in effect magnifying the deflection of said initial

electron beam, electron multiplier means, and an apertured electrode positioned between said curved surface and said multiplier means for passing electrons emitted by said curved surface in accordance with the degree of deflection.

5. A space discharge device including means for developing and focusing an electron beam, means for deflecting said electron beam in accordance with a signal, an element having a secondary electron emissive outwardly curved surface interposed into the path of said electron beam, an electron multiplier mounted adjacent said secondary emissive curved surface to receive secondary electrons liberated by said beam from said surface, and a shield having an aperture interposed between said surface and said multiplier, said aperture being arranged to pass a selected portion of the secondary electrons liberated from said surface, thereby to make the number of secondary electrons passing through said aperture dependent upon the deflection of said beam.

6. A space discharge device including means for developing and focusing an electron beam, means for deflecting said electron beam in accordance with a signal, an element having a secondary electron emissive convex surface interposed into the path of said electron beam, an electron multiplier mounted adjacent said secondary emissive curved surface to receive secondary electrons liberated by said beam from said surface, and a shield having an aperture interposed between said surface and said multiplier, said aperture being arranged so that substantially no secondary electrons will pass therethrough when said beam is in its normal undeflected position.

7. A space discharge device including means for developing an electron beam, means for deflecting said electron beam in accordance with a signal, an element having a secondary electron emissive curved surface interposed into the path of said electron beam to obtain a cumulative deflection of said beam, and an electron multiplier mounted adjacent said secondary emissive curved surface to receive secondary electrons

from predetermined directions, said secondary electrons being liberated by said beam from said surface, said multiplier including a first stage having a secondary electron emissive surface facing said curved surface so that the number of secondary electrons liberated therefrom varies in accordance with the deflection of said beam.

8. A space discharge device including means for developing and focusing an electron beam, means for deflecting said electron beam in accordance with a signal, an element having a secondary electron emissive convex surface interposed into the path of said electron beam, and an electron multiplier mounted adjacent said secondary emissive curved surface to receive secondary electrons from predetermined directions, said secondary electrons being liberated by said beam from said surface, said multiplier including a first stage having a secondary electron emissive surface facing said curved surface so that the secondary emission factor varies therewith, thereby to provide an output current from said multiplier varying in accordance with the deflection of said beam.
